CLAIM

I claim the ornamental design for a ring, as shown and described.

DESCRIPTION

FIG. 1 is a Perspective view of a ring showing my new design;

FIG. 2 is a Front view of the ring as shown in FIG. 1;

FIG. 3 is a Back view of the ring as shown in FIG. 1;

FIG. 4 is a Left-side view of the ring as shown in FIG. 1;

FIG. 5 is a Right-side view of the ring as shown in FIG. 1;

FIG. 6 is a Top view of the ring as shown in FIG. 1; and,

FIG. 7 is a Bottom view of the ring as shown in FIG. 1.

The broken lines shown in the drawings represent portions of the ring which form no part of the claimed design.
